UNITED STATES PATENT OFFICE.

HOWARD M. DUDLEY, OF PHILADELPHIA, PENNSYLVANIA.

FIBER-TREATING DEVICE.

1,304,862.

Specification of Letters Patent. Patented May 27, 1919.

Application filed June 15, 1918. Serial No. 240,219.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Fiber-Treating Devices, of which the following is a full, clear, and exact specification.

10 My invention relates to dyeing devices and refers particularly to devices suitable for the dyeing or treating with liquids of wound fiber forms, such as warp balls, cops, etc.

15 The successful dyeing of wound fibers is dependent upon the equal and uniform passage of the dye liquor through the wound fiber mass and my invention presents a device whereby this may be readily and economically accomplished.

20 One of the objects of my invention is a foraminous device around which the fiber is wound.

25 Another object of my invention is a device in which the dyeing liquid may be caused to pass evenly and uniformly through the device upon which the fiber is wound, and hence evenly and uniformly through the fiber wound thereon.

30 Another object of my invention is a foraminous device upon which the fiber is wound and which will allow the compression of a series of such wound fibers and the uniform passage of a liquid therethrough.

35 Another object of my invention is a device in which the wound fiber after compression will be held in a fixed position free from disturbance during the passage of the liquid therethrough.

40 These and other objects of my invention will be evident upon a consideration of the specification and drawings.

As each individual warp ball, cop, or similar form contains only a limited length of fiber, it is essential that a number of such forms be treated simultaneously in order that the operation may be economical, and as the passage of a liquid through such a fiber mass in one direction only is liable to form liquid passages through which the liquid passes more freely than through the other portions, it is advantageous to employ a device which will allow of the passage of such liquid in reverse directions through the fiber mass.

55 My invention discloses a device whereby

these advantageous results may be obtained, and comprises broadly a foraminous spindle with compressible and extensible sides, within which spindle is a hollow foraminous 60 core capable of evenly diffusing a liquid through the foraminous spindle.

In the accompanying drawings illustrating one form of my device, similar parts are designated by similar numerals.

65 Figure 1 is a vertical cross-section of one form of my device inclosed in a dyeing receptacle.

70 Fig. 2 is a top plan view of my device with the fiber wound thereon.

75 Fig. 3 is a section through the line 3—3 of Fig. 2 showing two foraminous spindles and cores.

Fig. 4 is a broken enlarged side plan view of the spiral member with the bar 75 through which it passes.

80 Fig. 5 is a cross-section of a modified form of bar and the spiral member passing therethrough.

Fig. 6 is a broken top plan view showing 80 the positioning members of the spindle bars.

The particular form of the spindle of my device, illustrated in the accompanying drawings, comprises a spiral spring 10 passing through openings 11, 11 in a series of 85 extended members, or bars, 12, 12, the holes 11, 11 being sufficiently large to allow of the free movement of the spiral spring 10 therethrough.

90 The end of the spiral spring 10 is curved inwardly to allow it to pass a bar 12. Each bar 12 carries a series of extended members 12', 12' to prevent the bars from sliding toward each other into positions less than the length of the members 12', 12', the object 95 of the members 12', 12' being to prevent the bars 12, 12 from sliding together and thus causing a collapse of the spindle.

95 The core of the device as illustrated, comprises a hollow foraminous member 13 formed by a series of inwardly and outwardly extended angular members having vertical openings 14, 14 upon one side thereof and horizontal openings 15, 15 upon the other side thereof.

100 The method of arranging the spindles and cores, and of passing a liquid through them in reverse directions, is shown in Fig. 1. This device comprises a dyeing chamber 16 formed by the hollow cylindrical member 17, having the flanges 18 and 19. The flange 19 is attached to the flange 20 of the bot-

tom 21 by means of the screw bolts 22, 22. The bottom 21 is connected by means of the pipe 23 to a source of liquid supply and is also connected to the drain pipe 24, carrying 5 the valve 25. The flange 18 is movably connected to the flange 26 of the top 27, by means of the wing-screw bolts 28, 28, which pass through an opening in the flange 26 and thread within an opening in the flange 18. A pipe 29 connects the top 27 with a 10 source of liquid supply. The top 27 has an annular partition 30 which is extended inwardly into the stepped member 31, 32, 33. The annular hollow step 31 forms a tubular 15 opening 34. The step 32 has two inwardly extended members 35 and 36 spaced from each other and forming a recess 37. The member 36 conforms to the serrated outline of the core 13. The top 27 also contains an 20 extended annular member 38 capable of close engagement with the inner face of the tubular member 17 and slidably thereon.

Integral with the lower portion of the interior of the cylinder 17 is an annular member 38 and its supporting members 39, 39. The member 38 has the two inwardly extended members 40 and 41 spaced from each other and forming the recess 42. The member 41 conforms to the serrated outline of 30 the core 13.

The operation of the device is as follows:

A series of spindles is wound with the fiber 100, 100. A core is then placed within the dyeing receptacle, the outer face of the 35 lower portion of which abuts tightly upon the inner face of the member 41, forming a tight joint therewith. A series of wound spindles is then placed within the dyeing chamber and around the core 13, the extended members 12, 12 of adjacent spindles being staggered with respect to each other and the lower extended members 12, 12 of the lower spindle being situated within the 40 recess 42. The top 27 is then placed upon 45 the device, the upper extended members of the upper spindle being situated within the recess 37.

The top 27 is then moved inwardly by means of the wing screw bolts 28, 28. By 50 this means the member 33 presses downwardly upon the top wound fiber, thus compressing all of the wound fibers within the dyeing chamber, the annular member 38 making a tight joint within the cylindrical member 17.

As the fiber is thus compressed, it is forced against the extended members 12, 12 which are held tightly thereagainst by means of the spiral spring 10, thus holding 55 the fiber free from movement during the dyeing operation. A dye liquor is then forced through the pipe 23 and thus passes through the bottom 21, the dyeing chamber 16, the wound fiber 100, the foraminous spindle into the interior of the foraminous core

from which it passes through the tubular member 34 into the top 27 and through the pipe 29 for continuous circulation.

If the flow of liquid be reversed, it will pass through the pipe 29 into the top 27 and 70 thence through the tubular member 34 into the interior of the core 13, and thence outwardly through the foraminous core, the foraminous spindle, and the wound fiber into the receptacle 16 from which it passes 75 through the bottom 21 and the pipe 23 for continuous circulation.

It is to be noted that the construction of the foraminous core 13 is of such a character as to allow the liquid passing therethrough to be impinged equally and evenly over the inner surface of the wound fibers and that the construction of the spindle is such as to allow this equal and uniform impinging of the liquid to be unimpeded, thus 85 allowing the circulation of the liquid to be even and uniform through all portions of the various wound fibers.

In Fig. 5, the cylindrical bars 12, 12 are replaced by semi-cylindrical bars, one of 90 which 50 is shown herewith.

I do not limit myself to the particular size, shape, number or arrangement of parts as described and shown, all of which may be varied without going beyond the scope 95 of my invention as described and claimed.

What I claim is:—

1. In a fiber treating device, in combination, a spindle comprising a spiral spring carrying a series of spaced members. 100
2. In a fiber treating device, in combination, a spindle comprising a spiral spring carrying a series of spaced bars. 105
3. In a fiber treating device, in combination, a series of spaced members having openings therethrough and a spiral spring passing through said openings and supporting said members. 110
4. In a fiber treating device, in combination, a series of spaced bars having openings therethrough and a spiral spring passing through said openings and supporting the bars. 115
5. In a fiber treating device, in combination, a hollow foraminous core, a foraminous spindle spaced from the core and comprising a spiral spring carrying a series of spaced members. 120
6. In a fiber treating device, in combination, a hollow foraminous core, a foraminous spindle spaced from the core and comprising a spiral spring carrying a series of spaced bars. 125
7. In a fiber treating device, in combination, an angular hollow foraminous core, a foraminous spindle spaced from the core and comprising a spiral spring carrying a series of spaced members. 130
8. In a fiber treating device, in combination, an angular hollow foraminous core, a

foraminous spindle spaced from the core and comprising a spiral spring carrying a series of spaced bars.

9. In a fiber treating device, in combination, a hollow foraminous core, a foraminous spindle spaced from the core and comprising a series of spaced members having openings therethrough and a spiral spring passing through said openings and supporting said members.

10. In a fiber treating device, in combina-

tion, a hollow foraminous core, a foraminous spindle spaced from the core and comprising a series of spaced bars having openings therethrough and a spiral spring passing through said openings and supporting said bars. 15

Signed at New York city in the county of New York and State of New York this 4th day of May, 1918.

HOWARD M. DUDLEY.
